TELEVISION SYSTEM

Everhard H. B. Bartelink, Niskayuna, N. Y., assignor to General Electric Company, a corporation of New York

Application August 3, 1940, Serial No. 350,643

33 Claims. (Cl. 178—5.6)

This invention relates to signalling systems and more particularly to systems in which an amplitude modulated wave is transmitted recurrently.

In the television art as it has at present been standardized in this country, each successive frame or complete picture image is scanned in 441 lines, and 30 complete images are transmitted per second. The maximum amplitude of the wave transmitted corresponds to a black spot in the image. At the end of each line and between each frame there are transmitted respectively horizontal and vertical pedestal and synchronizing impulses which have respectively, intensities of 80% and 100% of the maximum carrier amplitude. Such a system requires the transmission of high frequency video signals of the order of 4 megacycles as side bands on at least one side of the carrier. It has been found feasible to transmit a carrier wave having such a wide side band range only in the ultra-high frequency region. Even in this region, however, frequency range is not unlimited, and it is very desirable to utilize the available space as completely as possible. It is accordingly an object of my invention to provide a radio signalling system for transmitting a greater amount of intelligence per unit time within a certain frequency range.

It is a further object of my invention to provide a television system in which additional information is transmitted during transmission of the pedestal impulses. In the attainment of these objects I find it desirable to shift the frequency of the carrier wave during a pedestal while maintaining it at maximum intensity, to produce a synchronizing impulse at the television receiver. The carrier frequency may, for example, be shifted into one band to produce a vertical synchronizing impulse and may be shifted into a different band to produce a horizontal synchronizing impulse, both bands being within the side band range produced by amplitude modulation of the wave by the video signal. It is an object of my invention to utilize a carrier wave, shifted into such a plurality of different frequency bands, to transmit at least one channel of information, such as an audio signal, in each frequency band.

It has been found desirable to transmit a vertical pedestal impulse, whose duration is equal to about 15 to 25 horizontal lines in the image, in order to allow apparatus in the transmitter and receiver to become reconditioned to begin transmission of an entire new image. If double interlaced scanning be used, such a vertical pedestal impulse occurs 60 times each second. Dur-

ing such a vertical pedestal impulse, the transmission of horizontal synchronizing impulses is continued and vertical synchronization may be effected by a train of pulses interspersed with the horizontal synchronizing pulses. It is an object of my invention to transmit at least one signal by means of such trains of impulses.

It is a corollary object of my invention to provide suitable mechanism for transmitting more than one signal through such trains of pulses transmitted in a single frequency band.

In the transmission of horizontal synchronizing impulses by shifting the frequency of the carrier wave into a certain range, false synchronization may be effected by means of waves of similar frequency characteristic existing in the video signal or in atmospheric disturbances or the like. A way of reducing the possibility of such false synchronization has been described in my copending application for U. S. Letters Patent S. N. 331,349, filed April 24, 1940, for Image transmission systems, and assigned to the same assignee as the present application. In that previous application there is disclosed and claimed an improved method and apparatus for transmitting and receiving a television signal having synchronizing impulses. In that application there is disclosed receiving apparatus for discriminating between a wave when its frequency is modulated and when its amplitude is modulated, so that substantially no energy is received except when the wave is frequency modulated. The possibility of synchronization by fortuitous frequency characteristics of the wave when amplitude modulated is therefore reduced. It is an object of my invention further to minimize the possibility of such false synchronization in a system such as here described. In the attainment of this object it is convenient to transmit simultaneously two separate horizontal synchronizing impulses by shifting the carrier wave into at least two individual frequency bands, within each of which bands additional information may be imposed on that respective portion of the carrier. It is also an object of my invention to provide a simple circuit for effecting horizontal synchronization in a receiver only when the carrier wave appears simultaneously in two or more predetermined frequency bands.

The features of my invention which I believe to be novel are set forth with particularity in the appended claims. My invention itself, however, together with further objects and advantages thereof may best be understood by reference to the following description taken in connection

with the accompanying drawings in which Fig. 1 is a simplified schematic diagram of a radio transmitter embodying my invention; Fig. 2 is a simplified schematic diagram of a radio receiver adapted to receive a wave transmitted by the transmitter of Fig. 1; Fig. 3 is a simplified schematic diagram of a more elaborate radio transmitter embodying my invention; Fig. 4 is a receiver adapted to receive a wave transmitted by the transmitter of Fig. 3; and Fig. 5 is a detailed schematic view of a certain portion of the transmitter of Fig. 3.

In Fig. 1 there is illustrated a television transmitter having a camera tube 10 connected through an amplifier and pedestal injector 11 to an amplitude modulator 12. The modulator 12 modulates the amplitude of a carrier wave from a master oscillator 13 in accordance with the intensity of video impulses produced by the camera tube 10. The modulated carrier wave from the modulator 12 is radiated from an antenna 14.

Suitable apparatus is provided for controlling the horizontal and vertical scanning and framing of the camera tube 10, which apparatus comprises a horizontal and vertical deflection and synchronizing signal generator 15. The generator 15 transmits horizontal and vertical deflection waves respectively to a magnetic yoke surrounding a portion of the camera tube 10 and including deflection coils 16 and 17. The generator 15 also produces horizontal and vertical pedestal impulses which are mixed in a pedestal mixer 18 and injected into the video signal through the amplifier and pedestal injector 11. The video signal, complete with horizontal and vertical pedestals, is of usual form and need not be explained. The horizontal and vertical pedestals are also separately transmitted to apparatus for shifting the carrier frequency during the existence of pedestals, so that the intensities of the shifted carriers are modulated distinctively in order to transmit respectively horizontal and vertical synchronizing impulses.

The apparatus for shifting the carrier frequency respectively to different bands during horizontal and vertical pedestals comprises a horizontal band generator 19, a vertical band generator 20, and four balanced modulators 21, 22, 23, and 24. The carrier wave from the master oscillator 13 is transmitted through the balanced modulator 21 and then through the balanced modulator 23 to an amplifier 25, which amplifies the carrier wave and impresses it on the amplitude modulator 12. Since each of the balanced modulators 21, 22, 23, and 24 is identical in construction, only the first will be described in detail.

The modulator 21 comprises a pair of electron discharge devices 26 and 27 which are connected to be energized in balanced or push-pull relation through a transformer 28 from the master oscillator 13. The cathodes of the devices 26 and 27 are connected together and through a source 29 of grid bias potential and a grid resistor 30 in series to the center tap of the secondary of transformer 28. The anodes of the devices 26 and 27 are connected in push-pull relation to an output transformer 31, whose center tap is connected through a source 32 of anode potential to the cathodes of the two devices.

The source 29 of grid bias potential normally supplies a grid bias to the devices 26 and 27, suitable for amplification of the wave from the master oscillator 13 which is supplied to the output transformer 31. The horizontal impulses from

the generator 15 are impressed through a coupling condenser 33 across the grid resistor 30 and have such magnitude and polarity as to drive the grids of the devices 26 and 27 to cutoff.

5 At the same time the horizontal pedestal impulses are impressed through a phase reversing discharge device 34 and a coupling condenser 35 upon the grid resistor 36 of the balanced modulator 22. The source 37 of grid bias potential in the balanced modulator 22 is of sufficient size and of such polarity as to maintain the discharge devices 38 and 39 in the balanced modulator 22 at or beyond cutoff. The horizontal pedestal impulses, which recurrently prevent transmission 10 of the carrier wave through the modulator 21, act in reverse polarity on the modulator 22, so as to make the grids of the devices 38 and 39 less negative and thus allow these devices to amplify the carrier wave from the horizontal band generator 19.

The wave from the generator 19 is transmitted through the output transformer 40 of the modulator 22, which transformer is connected in series with the output transformer 31 and with the input transformer 41 of the balanced modulator 23. The source 42 of grid bias potential for the modulator 23 and the source 43 of grid bias potential for the modulator 24 are adjusted in the same ways, respectively, as the sources 29 and 37 in the modulators 21 and 22. The output transformer 44 of the modulator 23 and the output transformer 45 of the modulator 24 are connected in series with each other and with the input to the amplifier 25.

35 In operation, during any particular horizontal deflection of the scanning cathode beam in the camera tube 10, video impulses modulate the amplitude of the carrier wave from the master oscillator 13. The generator 15 produces no horizontal or vertical pedestal impulses, and the balanced modulators 22 and 24 remain in a blocked condition, so that the waves from the generators 19 and 20 are not transmitted. The balanced modulators 21 and 23, however, are in 40 condition for transmitting the carrier wave from the master oscillator 13, first through the balanced modulator 21, and then through the modulator 23 to the amplifier 25, and to the amplitude modulator 12.

50 At the end of a horizontal deflection of the cathode ray beam in the tube 10, a horizontal pedestal impulse appears which, through the amplitude modulator 12, raises the radiated intensity of the carrier to a maximum and thus blocks out all video signals during its existence, and at the same time changes the balanced modulator 21 to a blocked condition and the balanced modulator 22 to a condition for transmitting a wave. The carrier wave from the master oscillator 13 is therefore no longer transmitted, while the shifted carrier wave from the horizontal band generator 19 representing a horizontal synchronizing impulse passes first through the balanced modulator 22 and then through the balanced modulator 23 to the amplifier 25 and amplitude modulator 12.

60 After a single complete frame or image has been completely scanned horizontally in a succession of horizontal lines, the generator 15 produces a vertical pedestal impulse which, like the horizontal pedestal, increases the intensity of the carrier wave passing through the modulator 12 to a maximum and blocks all video signals. The vertical pedestal at the same time changes the balanced modulator 23 to a blocked condition and 65 renders the balanced modulator 24 capable of

transmitting the carrier wave from the vertical band generator 20 to the amplifier 25 and the amplitude modulator 12. The pulse of shifted carrier frequency from generator 20 represents a vertical synchronizing impulse. Since the generator 20 produces a carrier wave whose frequency is shifted to a different band than the wave produced by the generator 19, horizontal and vertical synchronizing impulses are different.

While the carrier wave is being produced respectively by the horizontal band generator 19 and the vertical band generator 20, additional information may be carried by impressing frequency modulation on the carrier wave within each of these two bands. For example, the audio wave, which it is usually desired to transmit along with the video signals from the camera tube 10, may be picked up by a microphone 46, amplified by audio amplifier 47, and impressed upon a capacity tube 48, which is connected in the tuned circuit of the horizontal band generator 19. The capacity tube 48 may be any device whose capacity, or if it be desired, whose inductance changes in response to the intensity of a wave impressed thereon. Electron discharge circuits are well known in which a discharge device is arranged to simulate either an inductance or a capacity, the magnitude of which may be varied in accordance with a desired signal. Such a device may be used to advantage in this application. The capacity tube 48 and the horizontal band generator 19 are so adjusted that frequency modulation of the carrier wave by audio signals never causes the wave to change in frequency enough to leave the band assigned to the carrier wave for transmission of the horizontal synchronizing impulse.

Since in the present standard system the horizontal synchronizing impulse are sent somewhat more than 13,000 times per second, they are of sufficiently high frequency to be modulated in response to audio signals. It has been found that audio signals may be satisfactorily reproduced by transmission interrupted at such a rate.

Similar apparatus is provided for shifting the frequency of the carrier wave produced by the vertical band generator 20 to transmit a measure of the average brightness of the picture being televised. For this purpose a photocell 49 is placed near the camera tube 10 so as to produce a voltage proportional to the average amount of light on the camera tube. The output of the photocell 49 is amplified through an amplifier 50 and changes the capacity, or inductance, of a capacity tube 51 which is connected in the tuned circuit of the vertical band generator 20. This apparatus for transmitting a measure of average brightness is adjusted so that the carrier wave during transmission of vertical pedestals never leaves the frequency band assigned to the transmission of vertical synchronizing signals. Since the average brightness of a scene changes relatively slowly and particularly since the eye cannot distinguish changes as rapidly as thirty times per second, the transmission of a measure of brightness by the vertical band generator 20 and its associated apparatus once every sixteenth of a second is ample for the purpose of maintaining the received picture at a suitable degree of brightness.

Since a side band produced by amplitude modulation of an unshifted carrier may occupy a modulation band within four megacycles of the unshifted carrier, it is desirable that a frequency band no greater than this shall be occupied by the shifted carrier wave produced by the gener-

ators 19 and 20. By the term "modulation band" is meant the frequency band within which components of substantial intensity of a modulated carrier wave may be found.

5 The carrier wave may be modulated either in frequency or in amplitude within the meaning of this term. The frequency band between three and four megacycles from the unshifted carrier may be occupied by the wave from the horizontal band generator 19. If it be assumed that the microphone 46 and the remaining parts of the audio channel are capable of transmitting audio waves up to 10,000 cycles, the frequency modulated carrier wave produced by the audio signals may have a ratio of sweep frequency to audio frequency of about 1000 to one. Satisfactory noise suppression may be obtained with a much smaller sweep ratio, and if such a smaller ratio be used, the carrier wave may be transmitted as several different carrier waves, each having a frequency in a different frequency band. In each of these bands the respective carrier is frequency modulated with a smaller sweep ratio. The manner in which this is accomplished will be set forth hereinafter in greater detail.

25 It may be thought advantageous to reduce the sweep ratio by transmitting components of the audio signal or modulating wave up to a much higher frequency, rather than reducing the frequency band occupied by the wave. There is, however, a limitation to the maximum frequency which may be transmitted through any single frequency band. This limitation arises because the carrier wave is frequency modulated by audio signals during the existence of horizontal pedestals only, which occur at about the rate of 13 kilocycles per second. The audio signals are therefore effectively modulated on a 13 kilocycle carrier, and it is undesirable to transmit an audio frequency wave which approaches 13 kilocycles. It is, in fact, preferred to transmit no audio frequency wave near or above half that frequency, namely, 6½ kilocycles. This is in order to prevent the second harmonic of any 40 audio signal wave from heterodyning with the 13 kilocycle horizontal synchronizing signal to produce audible heterodyne waves.

45 If it be desired to transmit an audio signal with higher fidelity than that obtainable within such a 6 kilocycle band, the carrier wave, split into two or more individual frequency bands, may be respectively frequency modulated by individual portions of the high fidelity audio signal. For example, that portion of the carrier wave which lies within one frequency band may be modulated in frequency by components of the audio signal wave between zero and 5000 cycles. Another portion of the carrier wave which lies within a second frequency band may be modulated in frequency by other components of the high fidelity audio signal wave between 5000 and 10,000 cycles. The audio signal components between 5000 and 10,000 cycles, before modulating the frequency of that 55 portion of the carrier wave in the corresponding frequency band, are heterodyned with a suitable wave so that their frequencies, as transmitted, lie between zero and 5000 cycles. Of course, even higher frequency components of an audio signal wave may be transmitted by provision of more of such split audio channels.

70 In the large majority of audio signals which it is desired to transmit, it is entirely unnecessary that any frequency components over 6000 cycles be transmitted. For most audio signals it is

unnecessary to transmit frequencies over 2000 cycles to obtain good intelligibility. Satisfactory reproduction of most music is obtained through commercial broadcasting systems, which frequently do not transmit more than 4500 or 5000 cycles of an audio signal because of the necessity of operating such commercial transmitting stations in narrow frequency bands.

The effective suppression of noise or atmospherics in audio signals transmitted through the present system makes it appear that an audio signal of greater fidelity is transmitted than one in a range of frequencies up to 6000 cycles. With suitable limiting action in the frequency demodulation portion of the receiver, the present system using a frequency modulated wave is capable of a high degree of noise or atmospheric suppression.

For transmission of the carrier wave from the vertical band generator 20, frequency modulated by the measure of average brightness, a frequency band between two and three megacycles from the unshifted carrier may be employed. Since the measure of average brightness changes very slowly there is in this case a higher degree of freedom from atmospheric disturbances than for the audio signal, discussed above.

It has been shown how a television signal, complete with video signal, horizontal and vertical synchronizing impulses, and brightness control, as well as an audio signal, may be transmitted entirely within the frequency band occupied by side bands produced by amplitude modulation of a carrier wave by such video signals. The video signal and the horizontal and vertical pedestals are all amplitude modulated on the carrier wave, and the horizontal and vertical synchronizing signals, an audio signal, and a measure of average image brightness are all, in effect, frequency modulated upon the same carrier wave.

In Fig. 2 there is shown a receiver which is suitable for receiving the wave emitted by the transmitter illustrated in Fig. 1. This receiver includes an antenna 60, a tuner and amplifier 61, an amplifier and amplitude modulation detector 62, a brightness injector 63 and a cathode ray tube 64 for reproducing television images by synthesizing the image field under control of the video signals and the synchronizing pulses. These parts of the receiver are well known in construction and operation and they receive amplitude modulated signals which are tuned, amplified, detected, and reproduced as pictures in the usual way.

Additional apparatus in the receiver is provided to be responsive to a carrier wave when it is shifted to either the horizontal or the vertical frequency band to transmit the respective synchronizing impulses. This synchronizing apparatus is energized from the output of the tuner and amplifier 61 and includes an asymmetrical acceptance filter 65, a carrier rejection circuit 66, a bottom clipper 67, a first limiter device 68, and a second limiter device 69 and suitable circuits for deriving respectively the horizontal and vertical synchronizing signals and the brightness measurement and audio signal. The asymmetrical acceptance filter 65, carrier wave rejection circuit 66, and bottom clipper 67 are disclosed and claimed in my previously mentioned copending application for Letters Patent S. N. 331,349, for Image transmission system. In the present application these components perform functions

in addition to those disclosed in the above mentioned application.

As described in that application, a grid resistor 71 and a coupling condenser 70 of the bottom clipper 67 are proportioned so that the carrier wave of maximum intensity transmitted during horizontal and vertical pedestals is rectified and maintains a grid bias voltage on the grid of the bottom clipper 67. This bias is sufficient to prevent transmission of video signals, which, as side bands of the carrier wave, can theoretically never have more than half the intensity of the carrier. The bottom clipper 67 therefore acts to prevent transmission of any wave below a certain intensity and to allow transmission only of those portions of the wave above a predetermined intensity. The bottom clipper 67 thus constitutes an amplitude separator for segregating the line and frame synchronizing pulses from the camera or video signals.

The carrier rejection circuit 66 is designed to prevent transmission of the carrier wave at its normal frequency to the bottom clipper 67. It acts to minimize cross talk, which might otherwise occur in the bottom clipper 67, and it also lessens the amount of frequency discrimination which it is necessary to provide in tuned circuits following the bottom clipper 67.

The asymmetrical acceptance filter 65 is provided, as described in the above mentioned application, to guard against the possibility that side bands on opposite sides of the carrier wave might combine in intensity so as to be able to pass the bottom clipper 67.

The grid bias for the two limiter devices 68 and 69 is so adjusted that no portion of any wave above a certain intensity is transmitted to the respective output circuits. This limiter action is identical with that usually provided in frequency modulation receivers.

The output circuit of the first limiter device 68 includes, in series, the input 74 to a band pass filter 74 and the input 75 to a frequency modulation detector circuit 75. The band pass filter circuit 74 may be of any desired form and is so adjusted as to pass every wave lying within the band assigned for transmission of the vertical synchronizing signal. That is, it is so adjusted as to accept any wave produced by the vertical band generator 20 of Fig. 1. A detector 76 is connected to the output of the band filter 74 to rectify any wave passing therethrough and to apply it as a pulse to a vertical deflection generator 77 which is connected in any convenient way to control the vertical deflection of the cathode ray in the receiving picture tube 64.

The frequency modulation detector circuit 75 is of any desired form and is adjusted to transmit and demodulate any frequency modulated wave lying within the same frequency band to which the band filter 74 is responsive and which is produced by the vertical band generator 20. The operation of such frequency modulation detector circuits is well known. The circuit 75 produces a voltage across its output resistor 78, the magnitude of such voltages being dependent upon the frequency of the wave from the limiter device 68, which wave was produced by the vertical band generator 20. The voltage produced across the output resistor 78 is a measure of the average brightness of the transmitted image. This voltage is impressed upon the brightness injector 63 to control the intensities of the video signals passing from the amplifier and detector 62 to the receiving picture tube 64.

The output circuit of the second limiter device 69 passes serially through a second band pass filter circuit 79 and through a second frequency modulation detector circuit 80. The filter 79 is designed to transmit any wave within the band of frequencies produced by the horizontal band generator 19 shown in Fig. 1. That is, it is so adjusted as to transmit the carrier wave whenever it lies in the frequency band assigned to transmission of a horizontal synchronizing impulse. The output of the filter 79 is impressed upon a detector 81 similar to the detector 76 and which similarly produces a rectified impulse which corresponds to a horizontal synchronizing impulse produced in the transmitter. The impulse produced by the detector 81 is impressed upon a horizontal deflection generator 82, which operates in well known fashion to control the horizontal deflection of the cathode ray in the receiving picture tube 64.

The frequency modulation detector circuit 80 is similar to the detector circuit 75, except that it transmits and demodulates any wave whose frequency lies in the band which is passed by the filter 79 and which is generated by the horizontal band generator 19. The frequency modulation detector circuit 80 includes an output resistor 83, across which a voltage is produced whose magnitude is dependent upon the frequency of the carrier wave produced by the horizontal band generator 19. Thus, audio signals, which have at the transmitter produced frequency modulation of the carrier wave within the horizontal frequency band, appear across the output resistor 83. This audio signal is amplified through an audio amplifier 85 and is converted into a sound wave by a speaker 86. The image produced by the picture tube 64 may therefore be viewed at the same time as the sound produced by the speaker 86 is heard.

It will thus be seen that the system described including the transmitter and receiver accomplishes transmission of a television signal including a video signal, synchronizing impulses, and image brightness control along with an accompanying sound signal, all of the transmitted waves lying entirely within the side band range produced by amplitude modulation of the carrier by the video signal alone. Since it is normally necessary to shift the carrier frequency, in frequency modulating a wave by a sound signal, only about five times the frequency of the sound signal, the horizontal frequency band assigned for operation of the horizontal band generator 19 need be only about 50 kilocycles wide. With the present system having a side band frequency range of about 4 megacycles, about 40 such horizontal frequency bands are available in the frequency range between 2 and 4 megacycles, which range may most conveniently be utilized. Furthermore, it is feasible to transmit a considerable number of low frequency messages, such as teletype, facsimile, or the like, by means of the vertical synchronizing channel, as will be pointed out hereinafter.

It is desirable that the transmitter illustrated by Fig. 1 be adjusted to maintain transmission of the horizontal synchronizing impulses at all times. It is therefore convenient to adjust the horizontal and vertical deflection generator 15 to transmit vertical synchronizing signals during appropriate periods interspersed between horizontal synchronizing impulses. That is, when it is desired to transmit a vertical synchronizing

impulse, the carrier wave continues to be shifted recurrently to the horizontal synchronizing frequency by the transmitter, but, during intervals when the carrier wave would otherwise be at its normal frequency, it is additionally shifted by the transmitter to the frequency band assigned for transmission of vertical synchronizing impulses.

It is preferred to provide such a frequency shift 10 of the carrier wave, which represents at least a part of one vertical synchronizing impulse, at a time after a horizontal frequency shift of the carrier wave equal to a quarter of the time between two consecutive horizontal frequency shifts. 15 There may actually be about 14 to 24 such shifts of the carrier wave from its normal frequency to the vertical frequency band, which train of shifts collectively represents one vertical synchronizing impulse. One single set or train of these shifts 20 is transmitted to produce one vertical synchronizing impulse, while consecutive shifts of the carrier wave into the horizontal frequency band are maintained.

During the time when the carrier wave is 25 within the vertical frequency band, between any two horizontal frequency shifts of the carrier, its frequency may be modulated within the vertical frequency band by an individual low frequency message, such as brightness measure, automatic expansion or compression control for an audio channel, or a code telegraph message or the like. For example, during the first frequency shift to the vertical frequency band, in any single train of such shifts representing a single vertical synchronizing impulse, the frequency of the carrier wave in the vertical frequency band may be adjusted to represent a measure of the average image brightness. During the second frequency shift of the carrier in such a train, the frequency 30 of the carrier may be adjusted in the vertical frequency band to represent an automatic expansion control voltage, such as may be desired to aid in producing high fidelity transmission of the sound signal accompanying the television image. 35 The third frequency shift of the carrier in the train may be adjusted to represent a character in a code telegraph message transmitted, for example, at the rate of 60 characters per second. That is, transmission may be at the frequency of 40 the vertical synchronizing impulse. The fourth frequency shift may be adjusted so that the carrier wave frequency in the vertical frequency band represents a character in a second code message. Alternatively, the fourth shift may 45 represent a succeeding character in the first code message, if that message be transmitted twice as fast, or at twice the frequency of the vertical synchronizing impulse. The number of such messages which may be transmitted, or the number 50 of times one message may be speeded up, is at least equal to the number of frequency shifts of the carrier wave within the vertical frequency band produced during any single train of carrier frequency shifts, which represent a single vertical synchronizing impulse.

In Fig. 3, a transmitter for transmitting waves of such nature is illustrated in which only two main horizontal frequency bands are utilized for the transmission of audio signals and two successive frequency shifts of the carrier represent one vertical synchronizing impulse and are utilized for the transmission of brightness measurement and code telegraph impulses. It is to be understood that the audio signal channels repre-

sented by the main horizontal frequency bands may be multiplied many fold over those illustrated, as is indicated above. Likewise the brightness measurement and code telegraph channels transmitted by frequency modulation of the carrier wave during its successive frequency shifts, of which a train collectively represents a vertical synchronizing impulse, may be multiplied to transmit one character of a message during each frequency shift of the carrier wave in a much longer train of such shifts, corresponding in time to the vertical synchronizing impulse of long duration commonly used at present. Many parts of the transmitter illustrated in Fig. 3 are identical with those of Fig. 1 and are given like reference characters.

In this transmitter only the equipment for shifting the carrier wave frequency, in order to transmit horizontal and vertical synchronizing impulses, and the apparatus associated therewith for transmitting messages frequency modulated on the carrier wave during the carrier frequency shifts, differs from corresponding apparatus in the transmitter illustrated by Fig. 1. Only such equipment is therefore illustrated and described in detail. The balanced modulators 21 and 22 are, as they were previously, placed respectively in a blocked and in a transmitting condition upon the production of a horizontal synchronizing impulse from the generator 15.

The balanced modulator 22 serves to transmit three shifted portions of the carrier wave from three generators 90, 91 and 92, frequency modulated by three respective audio signals. All three wave portions from the generators 90, 91 and 92 lie at all times in a single main horizontal frequency band which may, as was explained previously, be about 50 kilocycles wide. The shifted carrier wave portion from the generator 90 is so adjusted in mean frequency that it lies always in a sub-channel, which may be designated as No. 1, and which occupies only one third of the main horizontal frequency band assigned to the three generators. The generator 91 produces a similar wave, and is so adjusted that the corresponding shifted carrier wave portion lies in a second sub-channel No. 2, which occupies a different third of the 50 kilocycle band assigned for this main channel. The generator 92 is adjusted to produce a shifted wave portion in a third sub-channel No. 3, occupying the remaining third of this main horizontal frequency band.

Microphones 93, 94, and 95 are associated respectively with the generators 90, 91, and 92 in the same way as is the microphone 46 in Fig. 1 associated, through the audio amplifier 47 and capacity tube 48, with the horizontal band generator 19. The audio signal from the microphone 93 modulates the frequency of the wave produced by the generator 90 within the sub-channel No. 1. Correspondingly the audio signals from microphones 94 and 95 modulate the frequencies of the wave produced by generators 91 and 92 only within the respective sub-channels Nos. 2 and 3.

Entirely satisfactory audio signals may be transmitted through such an arrangement, even though such a high degree of noise and atmospheric suppression as may be attained by the apparatus illustrated by Fig. 1 is not present. For ordinary telephone communication purposes it is unnecessary to transmit the high frequency components of audio signals above 2000 or 3000 cycles and even in commercial broadcasting very

few receivers are capable of reproducing more than about 3500 or 4000 cycles of the audio signal. If, therefore, the shifted carrier wave generated by the generators 90, 91, and 92 be modulated in frequency by audio signals of not over 3300 cycles, and a 5 to 1 ratio of carrier sweep frequency to audio frequency be maintained for good atmospheric suppression, the limits of the 50 kilocycle frequency band are not exceeded and satisfactory telephone channels are available. Such frequency limits and other exact quantities as are given in this specification are exemplary and are not to be taken as delimiting applicant's invention.

15 Additional shifted carrier wave portions in a second main horizontal frequency band of 50 kilocycles width may be transmitted from generators 96, 97, and 98 through a balanced modulator 99 to the amplifier 25. Each shifted carrier wave generated by the generators 96, 97, and 98 is adjusted to remain respectively in sub-channels Nos. 4, 5, and 6. The carrier wave portion within each of these sub-channels is modulated in frequency by an audio signal respectively from microphones 100, 101, and 102. The balanced modulator 99 operates identically with the balanced modulator 22 and is placed in condition for transmission of shifted carrier wave portions in response to the same horizontal synchronizing impulse, which is reversed in phase by the tube 34.

The generators 90, 91, 92, 96, 97, 98 and their associated audio signal sources, along with the balanced modulators 22 and 99, may be multiplied many times in number so that additional main horizontal channels are available, each including if desired one or several sub-channels. If only two main channels, as shown, are utilized, it may be of advantage to assign to each channel a frequency band of greater width in order to obtain a higher degree of noise suppression.

45 The balanced modulators 23 and 24, which are identical with those shown in Fig. 1, are placed respectively in blocked and transmitting condition by a vertical synchronizing impulse from the generator 15, as was the case with the transmitter of Fig. 1. However, the vertical synchronizing impulses are applied to the balanced modulators 23 and 24 through a channel selector switch 103, 50 to be described in detail hereafter, which operates to apply only the first vertical synchronizing impulse, in a train of such impulses collectively representing a vertical synchronizing signal, to the balanced modulators 23 and 24, and to apply 55 the second vertical synchronizing impulse in such a train to a pair of additional balanced modulators 104 and 105.

It is assumed with the circuits illustrated that only three successive shifts of the frequency of the carrier wave into the vertical synchronizing band are produced in a single train of such shifts, which corresponds to one complete vertical synchronizing signal. Usually many more individual shifts of the carrier frequency into the vertical synchronizing frequency band are necessary, or at least desirable, in one vertical synchronizing signal, and in such case additional pairs of balanced modulators such as modulators 23, 24, and 104, 105 may be provided, corresponding to additional low frequency information channels.

70 There is a slight difference between the transmitters of Figs. 1 and 3 in connections through the balanced modulators 21, 22, 23, and 24 to the amplifier 25; in that the carrier wave transmitted through the balanced modulator 22 is trans-

mitted directly to the amplifier 25, rather than first through the balanced modulator 23. If a system be used, as explained above, in which the carrier wave is shifted in frequency to the vertical frequency band during different periods from those when it is shifted to the horizontal band or bands, it is unnecessary to transmit the output of the balanced modulator 22 through the modulator 23. In such a system the balanced modulator 22 is never conditioned for transmission of waves, when the balanced modulator 23 is in a blocked condition.

Only one vertical frequency band need be assigned for transmission of the several low frequency message channel carrier wave portions respectively through the balanced modulators 104, 105, and through other similar modulations, if they are used. This is true because the vertical frequency band is occupied by shifted carrier wave portions in the same frequency band but passing through the balanced modulators in turn and thus modulated in frequency successively by different message characters.

Only a rather small frequency band need be assigned for transmission of the vertical synchronizing signals, since the low frequency information channels transmitted through the vertical frequency band have a satisfactory degree of atmospheric suppression with only a small sweep frequency of the shifted carrier wave portions. This small channel for the vertical synchronizing impulses may be allocated at either extreme of the horizontal frequency bands, which carry horizontal synchronizing impulses and sound signals, or the like.

Three individual generators 106, 107, and 108 are adjusted to produce individual, shifted carrier wave portions within the vertical frequency band, and are connected to transmit these carrier waves through the balanced modulator 24 to the amplifier 25. Each of these generators is adjusted to operate in an individual portion of the vertical frequency band, in a manner similar to the three generators 90, 91, and 92 which operate in individual portions of their corresponding horizontal frequency band. For example, the generator 106 may be adjusted so that the shifted carrier wave portion which it produces lies always within a first part of the frequency band assigned for transmission of the vertical synchronizing impulse.

The first part of this vertical frequency band, during transmission of the first synchronizing impulse in a train of such impulses, may be conveniently termed the brightness measurement sub-channel. As illustrated, the wave generated by the generator 106 is modulated in frequency, within this brightness measurement sub-channel, in accordance with a voltage produced by the photocell 49 and amplified through the amplifier 50.

The generator 107 may be adjusted to produce a shifted carrier wave portion lying, in a similar manner, within a second part of the frequency band assigned for transmission of vertical synchronizing signals. The frequency of this shifted carrier wave portion, produced by the generator 107, may be modulated within its sub-channel, which may be designated as telegraph sub-channel No. 1, by any suitable code telegraph signal or the like.

A suitable code telegraph signal for such frequency modulation is, for example, a signal such as is utilized in transmitting messages by commercial teletype machines. Another low fre-

quency signal which may be suitably transmitted through such a sub-channel is a signal of the nature which is now called facsimile.

The generator 108 is adjusted to produce a shifted carrier wave portion within a sub-channel No. 2, which is the remaining part of the vertical frequency band, during transmission of the first vertical synchronizing impulse in a train of such impulses. This generator produces a wave whose frequency is modulated by a second low frequency message.

Three additional generators 109, 110, and 111 are provided, which generate shifted carrier wave portions respectively within the same three parts of the vertical frequency band as the generators 106, 107, and 108, but during transmission of the second vertical synchronizing impulse in a train of such impulses. There is no interference between the waves produced by these two sets of generators, since their output signals are transmitted to the amplifier 25 sequentially, and never at the same time. The channel selector switch 103, acting through the balanced modulators 24 and 105, controls the sequential transfer of the signals from those two sets of generators to the amplifier 25, in a manner to be explained later. Each of the generators 109, 110, and 111 is associated with apparatus for modulating the frequency of the wave portion produced by it within its respective portion of the vertical frequency band. This frequency modulation is in accordance with corresponding code telegraph messages or the like. Since the waves produced by the two sets of generators 106, 107, 108, and 109, 110, 111 do not mutually interfere, the frequency modulated waves produced by the generators 109, 110, 111 may be respectively designated as lying in sub-channels Nos. 3, 4, and 5.

Additional sub-channels similar to those just described may be made available in the system by a change in the channel selector switch 103 to select more channels periodically and successively and by the addition, for each additional set of one or more sub-channels, of another pair of balanced modulators similar to modulators 104 and 105 and their associated generators 109, 110, and 111.

It may be noted that the generators which produce carrier wave portions frequency modulated by audio signals, such as generators 90, 91, 92, 96, 97, and 98, all operate simultaneously but in different and individual portions of the total available frequency range, which preferably corresponds roughly to the side band range produced by amplitude modulation of the carrier wave by the video signal. If, as shown, six such generators are utilized, it is preferred that the shifted carrier wave portion produced by each is, when radiated from the antenna 14, of about one sixth the intensity of the unshifted carrier wave which originates in the master oscillator 13 and is impressed on the antenna 14.

For a similar reason, each of the generators 106, 107, and 108, which operate simultaneously, and also each of the generators 109, 110, and 111, which also operate simultaneously and separately from other generators, should produce radiation at the antenna 14 of their respective shifted carrier frequencies, which for each wave portion is about one third of the intensity of the normal frequency carrier wave controlled by the master oscillator 13.

By thus providing that the means for shifting the frequency of the carrier wave shall maintain the total intensity of all radiation from the

antenna 14 substantially constant and maximum during pedestal periods, the amplifier 25 and the amplitude modulator 12 are operated during the transmission of horizontal and vertical pedestals and synchronizing signals at full load and at maximum carrier intensity. Therefore, efficient transmission of a frequency modulated wave is achieved, and at the receiver the maximum intensity of the received wave is available to maintain horizontal and vertical synchronization, as well as to reproduce any other intelligence, such as audio signals, applied to the carrier wave during pedestal periods, when horizontal and vertical synchronization is effected.

Even though the pedestals, during which a shift of carrier frequency effects transmission of synchronizing impulses, exist during only about 15 per cent of the total time of transmission, the audio signals reproduced at the receiver are satisfactory because carrier intensity is maintained at its maximum value during transmission of such signals, as it is in conventional systems of transmission by frequency modulation. It is known that conventional frequency modulation transmitters may be low powered to produce the same received signal strength as a higher powered amplitude modulated transmitter whose side-band intensity is only a small fraction of its maximum carrier intensity.

It is a great advantage in the use of such a transmitter as is described herein that, not only the audio signal accompanying the television image is transmitted without the necessity for any extra carrier wave, but that a large number of additional audio signals as well as low frequency signals, are also transmitted. All these signals are transmitted on the same carrier wave as the television signal, and in a frequency range preferably not greater than that occupied by the side bands arising from amplitude modulation of the carrier wave by the video signal. It is, of course, highly desirable to dispense with the extra carrier normally used to transmit sound accompaniment for a television picture, not only to save the space which it takes up in the available frequency range, but to effect very substantial simplification of the receiver and savings in the cost of building and operating an extra transmitter.

More important yet, in a transmitter such as illustrated in Fig. 3, which is more efficiently used than that illustrated in Fig. 1, it is necessary to provide only one power amplifier and only one amplitude modulator stage and a single radiating antenna for transmission of a complete television picture and a large number of audio signals, as well as a number of low frequency messages.

Such a transmitter may be utilized for example to transmit one television signal with its accompanying sound, and may also transmit 8 or 10 commercial broadcast sound signals. On the remaining audio channels may be transmitted service telephone messages or the like and, on the low frequency message channels, signals such as teletype transmissions. A receiver may be installed in a home, which receiver is capable of receiving and reproducing the television image with its accompanying sound, or alternatively is capable of reproducing any of the eight or ten commercial broadcast sound signals.

At some distance from such a transmitter there may be placed a commercially operated receiver which may be designed to receive the signals described above and to supply all or part

of these signals to a nearby relay transmitter. This relay transmitter may be of the same nature as that illustrated in Fig. 3.

A receiver suitable for receiving the carrier wave transmitted by the apparatus illustrated by Fig. 3, and for reproducing all the signals impressed thereon, is illustrated in Fig. 4. Many of the components of this receiver are identical with those described in connection with the receiver of Fig. 2 and are given like reference characters. The asymmetrical acceptance filter 65 with the carrier rejection circuit 66 and the bottom clipper 67 operates in much the same way. However, there is one distinction since, when receiving a wave such as that transmitted by the transmitter of Fig. 3, the carrier wave during horizontal or vertical pedestal periods does not have a single frequency, but is in effect split up into portions which are individually shifted into a number of frequency bands.

It has been found that a bottom clipper, such as the clipper 67, when adjusted to transmit only portions of a wave of greater than a predetermined intensity, will transmit portions of several waves of different frequencies, none of whose individual intensities are as great as the predetermined intensity, but the sum of whose intensities exceeds the predetermined intensity even by a slight amount. It has been found, further, that the wave portions transmitted by such a bottom clipper are easily distinguishable according to their frequencies.

As a particular example of the operation of bottom clippers 67, let it be assumed that the six generators 90, 91, 92, 96, 97, and 98 in the transmitter of Fig. 3 are controlling the radiation of a carrier from the antenna 14. The carrier therefore has six component parts, each of a different frequency, and each of about one sixth the total carrier intensity. Let it also be assumed that the bottom clipper 67 is adjusted to reject any wave or combined waves, whose intensity is less than nine tenths of the total intensity of the carrier radiated by the antenna 14. The output of the bottom clipper 67 under such conditions contains six component parts whose respective frequencies are the same as the several frequencies at which the six generators 90, 91, 92, 96, 97, and 98 operate. These several frequencies can be readily separated by means of suitably tuned frequency discriminating circuits.

In the receiver illustrated, which is arranged to resolve the carrier wave emitted by the transmitter of Fig. 3, there are provided three band pass filters 120, 121, and 122 to serve as the tuned frequency discriminating circuits. Filter 120 is designed to accept waves in the frequency band controlled by the generators 90, 91, and 92 in the transmitter of Fig. 3. Filter 121 is designed to accept and transmit waves from the generators 96, 97, and 98. Filter 122 is designed to transmit waves from any of the generators 106 through 111 controlling the wave portions within the vertical frequency band, assigned to transmission of vertical synchronizing impulses.

These three filters 120, 121, and 122 are respectively energized from the output of the bottom clipper 67 through limiter devices 123, 124, and 125, which are so adjusted as to transmit to their respective filter a fixed portion of the output of the bottom clipper 67, except when the wave received by the antenna 60 decreases to a value near or below the threshold of the bottom clipper 67. The function of apparatus such as

the limiter devices 123, 124, and 125 in frequency modulation receivers is well understood.

The band pass filter 120, as explained above, transmits only waves in the same frequency band as the operating frequencies of the generators 90, 91, and 92 of Fig. 3. Apparatus, which will be explained in some detail, is connected to the output of the filter 120 for initiating a horizontal deflection of the cathode ray in the receiving picture tube 64, whenever energy appears in the corresponding frequency band. Additional audio reproducing apparatus is connected to the output of the filter 120 respectively to convert the frequency variations of the three waves from the generators 90, 91, and 92 in the transmitter of Fig. 3 into three corresponding audio signals.

The audio reproducing apparatus comprises three frequency discriminator circuits 126, 127, and 128 of any suitable form which are energized through a buffer amplifier 129 from the filter 120. The frequency discriminator circuits 126, 127, and 128 are respectively connected through audio amplifiers 130, 131, and 132 to speakers 133, 134, and 135. The speaker 133 reproduces audio signals which were originally converted into electrical impulses through the microphone 93 of Fig. 3. Correspondingly the speakers 134 and 135 respectively reproduce audio signals from microphones 94 and 95.

Although it may be provided that horizontal deflection of the cathode ray in the tube 64 is initiated in response to any wave lying within a single main horizontal frequency band, it is preferred to employ apparatus to initiate such horizontal deflection only when wave energy exists simultaneously in at least two different main horizontal frequency bands whose frequencies are preferably widely separated. By provision of two separate main horizontal frequency bands for interlocked synchronization, the possibility that video signals or atmospheric disturbances, having an appropriate frequency characteristic, may produce false synchronization, is substantially eliminated.

Such interlocked synchronization is provided as follows. The band pass filter 121, designed to transmit only waves in the same frequency band as waves generated by the generators 96, 97, and 98 of Fig. 3, is connected through a buffer amplifier 136 to a detector diode 137. This diode has an output circuit including a load resistor 138. Waves are similarly transmitted through the band pass filter 120 and through the buffer amplifier 129 to be rectified by a detector diode 139 which has an output circuit including a load resistor 140. The load resistors 138 and 140 are connected end to end with such polarity that when waves of about equal intensity are transmitted simultaneously through the filters 120 and 121, substantially no voltage exists across their free ends. Suitable apparatus responsive to the voltage across either resistor, but only responsive when no voltage appears across their free ends, is arranged to initiate operation of the horizontal deflection generator 82.

Such apparatus for initiating synchronization of the generator 82 comprises a buffer amplifier 141 which is connected to be energized from the voltage across the resistor 140 through a resistor 142 and is arranged to amplify that voltage and apply it to the horizontal deflection generator 82 to initiate production of a horizontal deflection wave for the picture tube 64. So long as the voltage across the resistor 140 corresponds to the horizontal deflection impulses produced

by the horizontal and vertical deflection and synchronizing signal generator 15 in Fig. 3, proper synchronization is maintained between generators 15 and 82. However, if for some cause a voltage appears across the resistor 140 which has no counterpart in the voltage from the generator 15, false synchronization may be effected. The chances are great that such extraneous voltages cannot ever appear simultaneously upon the resistors 138 and 140. Means is therefore provided to prevent synchronization of the generator 82 through the voltage wave appearing across the resistor 140, except when an identical voltage wave appears across the resistor 138.

This means comprises a diode 143 cooperating with the resistor 142. The diode 143 is connected from a point between the resistor 142 and the buffer amplifier 141 to the free end of the resistor 138. It is so poled as to conduct current when a voltage appears on the resistor 140 and no corresponding voltage appears on the resistor 138. When the diode 143 is conducting, sufficient current passes through the resistor 142 so that the voltage which exists on the resistor 140 and not on the resistor 138 is not repeated through the buffer amplifier 141 to the generator 82. The horizontal synchronizing circuits in the receiver therefore act to maintain horizontal synchronization only when energy simultaneously appears in at least two individual main horizontal frequency bands. It is to be understood that the circuit illustrated for performing this function is exemplary and that other circuits within the scope of the invention may be arranged to perform the same function.

The band pass filter 121, in addition to being connected through the diode 137 to impress a voltage across the resistor 138, also energizes three demodulating circuits 144, 145, and 146, which are arranged to demodulate the frequency modulated wave passing through the filter 121. These three demodulating circuits 144, 145, and 146 correspond in their own main horizontal frequency band to the demodulating circuits 126, 127, and 128 in their respective horizontal frequency band. Each of the circuits 144, 145, and 146 is adjusted respectively to respond to a wave from a corresponding one of the generators 96, 97, and 98 of Fig. 3, and they are provided with audio amplifiers and speakers similar to those provided for circuits 126, 127, and 128. Therefore the carrier wave portion which is frequency modulated by an audio signal impressed upon the microphone 100 in Fig. 3 is demodulated, for example, by the demodulating circuit 144 and the audio signal is reproduced by its associated speaker.

If the generators 97 and 98 of Fig. 3 be omitted and the demodulating circuits 145 and 146 of Fig. 4 be correspondingly omitted, an entire main horizontal frequency band may be utilized for the transmission of one audio signal. In such case the generator 96 should be adjusted so that the frequency modulated wave produced by it occupies the entire horizontal frequency band and consequently allows transmission of higher frequency components of the audio signal. Likewise, the demodulating circuit 144 should be designed to demodulate a frequency modulated wave occupying the corresponding entire main horizontal frequency band.

It is to be understood that many more than two main horizontal frequency bands may be provided within the side band range produced by

amplitude modulation of the carrier wave by the video signal, as has been pointed out above, so that accordingly additional band pass filters similar to filters 120 and 121 with their associated apparatus may be provided, one for each of the main horizontal frequency bands.

The output of the band pass filter 122, which comprises all waves in the vertical frequency band, is transmitted serially through a buffer amplifier 147, through three frequency demodulating circuits 148, 149, and 150, and through the switching device 162. The wave from the amplifier 147 also passes to a diode 151 to be rectified to form a vertical synchronizing signal, which is applied to the vertical deflection generator 71 to maintain its synchronization with the vertical deflection generator 15 in the transmitter of Fig. 3.

The three frequency demodulating circuits 148, 149, and 150 are respectively adjusted to reproduce signals which are frequency modulated upon carrier waves within the first, second, and third portions of the vertical frequency band, which three waves are respectively controlled by the generators 106, 107, and 108, in Fig. 3. The frequency demodulating circuit 148 includes a load resistor 152 across which a voltage is produced, which is a measure of the average picture brightness as viewed by the photocell 49 of Fig. 3.

The brightness measurement voltage across the resistor 152 is transmitted through an amplifier 153 to the brightness injector 63, where it performs a function explained in connection with the receiver of Fig. 2. Such a low frequency control circuit may similarly be used to control volume compression or expansion or the like in any of the circuits associated with the speakers 133, 134, 135, etc., or for other similar purposes. The frequency demodulating circuits 149 and 150 reproduce low frequency pulses, which control low frequency apparatus 154 and 155. Such apparatus may be, as explained above, printing teletype machines or facsimile receivers.

The three frequency demodulating circuits 148, 149, and 150 are arranged to respond only to the first pulse of carrier wave energy, or more accurately, only to the first shift of carrier wave frequency, within the vertical frequency band in a single train of such pulses or shifts representing a vertical synchronizing signal. Means are provided to prevent the energy of later pulses in a single train from affecting these circuits, and for applying these later arriving pulses to other successive circuits. In the apparatus illustrated only two successive pulses of energy in the vertical frequency band have been utilized, so that a shift from the circuits 148, 149, and 150 to only one other set of circuits is necessary during each train of pulses. If, however, as is usually desirable, there are a large number of successive pulses in each train of pulses forming a vertical pedestal, the apparatus illustrated may be duplicated to respond to additional pulses and to provide additional sub-channels in the vertical frequency band.

The apparatus for deenergizing the circuits 148, 149, and 150 after the first pulse in each vertical pedestal comprises a short circuiting device 156 connected across the circuits to by-pass energy therearound. A control bias for the device 156 is provided which maintains it in normally nonconductive condition. A pulse generator 157 is provided which is energized by the initial pulse in a vertical pedestal applied to the vertical deflection generator 71 so that it pro-

duces a pulse simultaneously with the occurrence of the second pulse of energy in each vertical pedestal. This pulse produced by the generator 157 is transmitted through a transformer 158 to control the short circuiting device 156 so that it bypasses current around the frequency demodulating circuits 148, 149, and 150.

Three additional telegraph receivers 159, 160, and 161 are provided, each of which is similar to the telegraph receiver including the frequency demodulating circuit 149 and the low frequency apparatus 154. These receivers are connected serially with the frequency discriminating circuits 148, 149, and 150 so as to receive energy from the filter 122. Current is normally bypassed around them by the switching device 162 whose control bias is normally such that it remains in a conducting condition. The pulse from the pulse generator 157, which makes the device 156 conducting, is applied to the switching device 162 through a transformer 163 in such polarity as to render it non-conducting. The second pulse in each train which appears through the band pass filter 122 therefore is transmitted through the buffer amplifier 147 and through the short circuiting device 156, to the receivers 159, 160, and 161 which then operate to demodulate and reproduce their respective low frequency characters.

The particular switching apparatus which is illustrated as controlling the energization of the telegraph receivers and the brightness measurement receiver from successive pulses in each vertical pedestal is a relatively simple mechanism when only two successive pulses are utilized. However, if about 15 to 25 pulses in each pedestal be employed to transmit separate messages, the switching apparatus becomes bulky and it may be desirable to utilize some other form of switching means, such, for example, as the channel selector switch 103 illustrated in connection with the transmitter of Fig. 3.

In Fig. 5 this channel selector switch 103 is schematically illustrated in some detail. This switch comprises a cathode ray tube 170 which has a deflecting electrode 171 arranged to sweep the cathode ray successively over three separate anodes 172, 173, and 174 as its potential becomes less positive. To keep the deflecting electrode 171 at a suitable positive potential for maintaining the cathode ray upon the anode 172, connection is made through a resistor 175 to a source 176 of operating potential. Apparatus is provided to reduce the potential of the electrode 171 in steps in response to successive pulses in a single train representing a vertical pedestal or synchronizing signal.

This apparatus comprises a condenser 177 which is charged through a diode 178 and a variable resistor 179 by vertical synchronizing pulses which originated at the generator 15 to which the diode 178 may be coupled through a coupling condenser 180. The condenser 177, which before the beginning of each train of pulses is discharged, is charged in successive increments as each pulse from the generator 15 passes through the diode 178.

A direct current amplifier 181 is arranged to amplify the voltage across the condenser 177, and to reduce the voltage of the deflecting electrode 171 as the charge is stored in condenser 177 and builds up in increments. The potential of the deflecting electrode 171 becomes less positive in corresponding increments, each of which, by adjusting resistor 179, is made to be of such

magnitude that the cathode ray moves in steps from the anode 172 to the anode 173, and then to the anode 174, and then to additional anodes if such be provided. The number of anodes provided corresponds to the number of different main vertical channels to be transmitted, plus one. It also corresponds to the number of pulses produced by the vertical synchronizing generator 15 in each vertical pedestal.

The anodes 172, 173, and 174 are maintained at positive potential by connections respectively through load resistors 182, 183, and 184. The anodes 172 and 173 are connected respectively to two exterior circuits which, as illustrated in Fig. 3, lead to the balanced modulators 23 and 24, and to balanced modulators 104 and 105, to control their successive operation.

The anode 174 is not connected to any exterior circuit, but is utilized to remove the charge from the condenser 177 at the end of each train of pulses from the generator 15, so as to return the cathode ray to the anode 172 and to condition the apparatus as a whole to be ready for a later train of pulses in a succeeding vertical pedestal. To accomplish this the anode 174 is connected through a resistor 185 to a direct current amplifier 186, which in turn is connected so that an amplified impulse from anode 174 operates a short circuiting device 187, arranged in shunt to the condenser 177. Condensers 188 and 189 are connected respectively from the two ends of the resistor 185 to ground.

These two condensers 188 and 189 are so proportioned relative to the magnitude of the resistors 184 and 185 that, when the cathode ray impinges on the anode 174 and its positive potential accordingly is reduced, the grid of the amplifier 186 remains long enough at a sufficiently reduced positive potential as to allow its anode to rise in potential from a highly negative, or cut-off, value for a certain time. When the anode of the amplifier 186 rises in potential, the short circuiting device 187 becomes conducting and, due to the resistors 184 and 185 and the condensers 188 and 189, remains in conducting condition long enough to discharge the condenser 177 substantially completely.

As suggested in connection with Figs. 3 and 4, the generator 15 may be adjusted to produce additional pulses in each train forming a vertical pedestal, thus allowing additional low frequency messages to be transmitted, if the balanced modulators 23, 24, 104, and 105 and other equipment be duplicated. It is then only necessary, in the channel selector switch 103 illustrated in Fig. 5, to provide additional anodes similar to the anodes 172 and 173 with their accompanying circuits.

While I have shown particular circuits and arrangements which are well adapted to perform their assigned functions, it is to be understood that in actual commercial practice, as such apparatus as I have described is further developed, other circuits embodying the same inventive concepts and performing the same functions but being physically smaller and simpler and costing less will be used. Also, as has been indicated above, in a receiver for use in a home it is not necessary, and in fact it is even undesirable, to include all the apparatus illustrated by Fig. 4. Conversely, in a receiver adapted for use in relaying, many of the circuits designed for utilization in home receivers may be undesirable.

While I have shown particular embodiments of my invention, it will, of course, be understood

that I do not wish to be limited thereto, since different modifications may be made both in the circuit arrangement and instrumentalities employed, and I aim in the appended claims to cover any such modifications as fall within the true spirit and scope of my invention.

What I claim as new and desire to secure by Letters Patent of the United States is:

1. In a television system utilizing an assigned 10 communication channel within a predetermined frequency band, the method comprising transmitting a carrier wave of predetermined frequency modulated in amplitude in response to a video signal during separate recurrent periods, the frequencies of said carrier wave and the side bands resulting from amplitude modulation thereof lying within said predetermined frequency band, transmitting a carrier wave whose frequency differs from said predetermined frequency and lies within said band during periods intervening between said recurrent periods, one characteristic of which wave is determined by a second signal, and concurrently modulating the frequency of said carrier wave within said band in response to a third signal.
2. In a television system utilizing an assigned 20 communication channel within a predetermined frequency band, the method comprising transmitting a carrier wave of predetermined frequency modulated in amplitude in response to a video signal during separate recurrent periods, the frequencies of said carrier wave and the side bands resulting from amplitude modulation thereof lying within said predetermined frequency band, transmitting a carrier wave whose frequency differs from said predetermined frequency and lies within said band during periods intervening between said recurrent periods, one characteristic of which wave is determined by a second signal, and concurrently modulating the frequency of said carrier wave within said band in response to a third signal only during said intervening periods.
3. In a television system the method comprising 30 transmitting a carrier wave modulated in amplitude in response to a video signal during separate regularly recurrent periods, the frequencies of said carrier wave and the side bands resulting from amplitude modulation thereof lying within a predetermined frequency band, transmitting a carrier wave whose frequency differs from the frequency of said first carrier wave and lies within said band during all periods intervening between said recurrent periods and concurrently modulating a characteristic of said carrier wave of different frequency in response to a second signal only during said intervening periods, said periods recurring at a frequency which is higher than the frequency of said second signal.
4. In a carrier television system, the method including transmitting a carrier wave only during separate recurrent periods, said carrier wave being modulated in response to a video signal, 40 transmitting a carrier wave whose frequency differs from the frequency of said first carrier wave only during periods intervening between said recurrent periods, and modulating a characteristic of said second carrier wave during said intervening periods.
5. In a carrier television system, the method including transmitting a carrier wave modulated in amplitude in response to a video signal during separate recurrent periods, the frequencies of 50 said carrier wave and the side bands resulting

from amplitude modulation thereof lying within a predetermined frequency band, transmitting a carrier wave whose frequency differs from the frequency of said first wave and lies within said band during periods intervening between said recurrent periods, and concurrently modulating the frequency of said second carrier wave in response to a second signal during said intervening periods.

6. In combination in a signalling system, a first signal source, means responsive thereto for modulating the amplitude of a carrier wave during recurrent periods, whereby a side band is produced having frequencies extending over a predetermined frequency range, a second signal source, means to modulate the frequency of a carrier wave during periods alternating with said recurrent periods over a frequency band within said predetermined frequency range in accordance with signals from said second signal source, a third signal source, and means to modulate the frequency of a carrier wave during said alternating periods over a second different frequency band within said predetermined frequency range in accordance with signals from said third signal source said periods recurring at a frequency which is higher than the frequency of signals from at least one of said sources.

7. In combination in a signaling system, a first signal source, means responsive thereto for modulating a characteristic of a carrier wave, whereby a side band is produced having frequencies extending over a predetermined frequency range, means to make said characteristic of said carrier wave constant during recurrent periods, means to shift the frequency of said carrier wave during said periods to a frequency within a second frequency range in the range of said side band, a second signal source, means to modulate the frequency of said carrier wave over said second frequency range in accordance with signals from said second signal source, and means for producing distinguishable responses corresponding respectively to the modulation of said characteristic, the frequency shift and the frequency modulation of said carrier waves, whereby the transmission of signals from said sources utilizes a minimum frequency range.

8. In combination in a television signaling system, a video signal source, means responsive thereto for modulating a characteristic of a carrier wave, whereby a side band is produced having frequencies extending over a predetermined frequency range, means to transmit said carrier wave without modulation during recurrent periods, a synchronizing signal source, means responsive thereto to shift the frequency of said carrier wave during said periods to a frequency within a second frequency range in the range of said side band, a third signal source, means to modulate the frequency of said carrier wave during said periods over said second frequency range in accordance with signals from said third signal source, and means for reproducing the signals from said sources in response respectively to the modulation of said characteristic, the frequency shift, and the frequency modulation of said carrier wave, whereby the transmission of said signals utilizes a minimum frequency range.

9. In combination in a signalling system, a carrier wave source, a first signal source, means responsive thereto to modulate a characteristic of said carrier wave, whereby a side band is produced having frequencies extending over a predetermined frequency range, means to transmit

said carrier wave without modulation of said characteristic during regularly recurrent periods, a second signal source, means to modulate the frequency of said carrier wave during said periods over a frequency range of predetermined width in accordance with signals from said second signal source, said period having a frequency of recurrence higher than the frequency of at least one of the signals from said signal sources,

5 10 and means to shift the frequency of said carrier wave during said periods to a frequency within the range of said side band such that said frequency range of predetermined width lies entirely within the predetermined frequency range 15 of said side band.

10. In combination in a television signalling system, a carrier wave source, a video signal source, means responsive thereto to modulate the amplitude of said carrier wave, whereby a side band is produced having frequencies extending over a predetermined frequency range, means to increase the amplitude of said carrier wave to a constant value during regularly recurrent periods, an audio signal source, means to modulate the 20 frequency of said carrier wave during said periods over a frequency range of predetermined width in accordance with signals from said audio signal source, said periods having a frequency of recurrence higher than the frequency of signals 25 from said audio signal source, and means to shift the frequency of said carrier wave during said periods to a frequency within the range of said side band such that said frequency range of predetermined width lies entirely within the predetermined frequency range of said side band.

11. In a television signalling system, a carrier wave source, a video signal source, means responsive thereto to modulate the amplitude of said carrier wave, whereby a side band is produced having frequencies extending over a predetermined frequency range, means to increase the amplitude of said carrier wave to a constant maximum value during recurrent periods, a synchronizing signal source, means responsive thereto during said periods to shift the frequency of said carrier wave to a frequency within the range of said side band, an audio signal source, and means to modulate the frequency of said carrier wave during said periods over a range within 50 the range of said side band in accordance with signals from said audio signal source.

12. In a signal transmission system, a signal channel, means to transmit through said channel a signal modulated carrier wave during regularly recurrent intervals, and means to transmit through said channel a plurality of signal modulated carrier waves during intervals alternating with said recurrent intervals, said recurrent intervals being substantially shorter in duration 55 than a cycle of the highest frequency of modulation of said plurality of carrier waves.

13. In a signal transmission system, means to transmit a signal modulated carrier wave during regularly recurrent intervals, and means to transmit a plurality of signal modulated carrier waves during intervals alternating with said recurrent intervals, the frequencies of said plurality of waves being spaced apart in the modulation band of said first wave by amounts comparable with 60 the respective modulation bands of said plurality of waves and said recurrent intervals being substantially shorter in duration than a cycle of the highest frequency of modulation of said plurality of waves.

75 14. In a signal transmission system, means to

transmit an amplitude modulated carrier wave during regularly recurrent intervals, and means to transmit a plurality of frequency modulated carrier waves during intervals alternating with said recurrent intervals, the frequencies of said plurality of waves being spaced apart in the modulation band of said amplitude modulated wave by amounts comparable with the respective modulation bands of said frequency modulated waves and said recurrent intervals being substantially shorter in duration than a cycle of the highest frequency of modulation of said plurality of waves.

15. In a television system, a video signal source, means to transmit a carrier wave amplitude modulated with signals from said source during regularly recurrent intervals, means to transmit a plurality of carrier waves during intervals alternating with said recurrent intervals, the total intensity of said plurality of waves being substantially equal to the unmodulated intensity of said first carrier wave, means to modulate the frequency of each of said plurality of carrier waves, the frequencies of said plurality of waves being spaced apart in the modulation band of said first wave by amounts comparable with the respective modulation bands of said plurality of waves and means responsive only to portions of said waves above a predetermined intensity less than said unmodulated intensity and greater than the intensity of any one of said plurality of waves for demodulating said plurality of frequency modulated waves.

16. In a television system in which video impulses and synchronizing impulses are produced, means to transmit a carrier wave modulated with said video impulses during regularly recurrent intervals, means responsive to said synchronizing impulses to transmit a plurality of carrier waves during intervals alternating with said recurrent intervals, and means to reproduce said synchronizing impulses from said plurality of carrier waves.

17. In a signal transmission system in which a signal modulated carrier wave is generated only during recurrent intervals and a plurality of signal modulated carrier waves are simultaneously generated only during intervals alternating with said recurrent intervals, the method which includes utilizing only portions of said waves above a predetermined intensity greater than the intensity of any of said plurality of waves.

18. In a signal transmission system in which an amplitude modulated carrier wave is generated only during recurrent intervals, and a plurality of frequency modulated carrier waves are simultaneously generated only during intervals alternating with said recurrent intervals, the method which includes utilizing only portions of said waves above a predetermined intensity greater than the intensity of one side band of said amplitude modulated carrier wave, whereby transmission of said frequency modulated carrier waves is maintained during the simultaneous transmission thereof and transmission of said side band is minimized.

19. In combination in signalling apparatus, means for transmitting a plurality of waves each lying in an individual frequency band, means individually responsive to each of said waves, and means to transmit to said responsive means only portions of said waves above a predetermined intensity less than the total intensity of said waves, whereby said responsive means

is unresponsive to any wave when the total intensity of said waves is less than said predetermined intensity and the response of said responsive means is minimized for waves whose total intensity is less than predetermined intensity during the absence of said plurality of waves.

20. In a signalling system, a carrier wave source producing a carrier wave in a predetermined frequency band, means to produce a succession of frequency shifts of said carrier wave during each of a series of recurrent periods to a different frequency band, a signal source, and means to modulate the frequency of said carrier wave during a respective frequency shift in each of said periods in accordance with signals from said signal source.

21. In a television signalling system, a carrier wave source, a synchronizing signal source, means responsive to synchronizing signals from said source thereof to produce a succession of frequency shifts of said carrier wave to a frequency different from the initial frequency of said carrier wave in each of a series of recurrent periods, a signal source, and means to modulate the frequency of said carrier wave during a respective frequency shift in each of said periods in accordance with signals from said signal source.

22. In combination in a signal receiver, means for transmitting a plurality of waves in different frequency bands simultaneously, a plurality of circuits tuned respectively to said frequency bands, and means to transmit said waves to said circuits, said last means transmitting portions of said waves when their total intensity is greater than a predetermined amount and blocking said waves when their total intensity is less than said predetermined amount, whereby the transmission of waves whose intensity is less than said predetermined amount is minimized during the absence of said plurality of waves.

23. In combination in a signal receiver, means to transmit a plurality of waves in individual frequency bands, a plurality of circuits respectively tuned to each of said frequency bands, and means to transmit said waves to said circuits, said last means comprising limiting means blocking transmission of portions of said waves above a predetermined intensity, and means transmitting portions of said waves when their total intensity is greater than a second predetermined intensity less than said first intensity, said last means blocking transmission of said waves when their total intensity is less than said second intensity, whereby transmission of waves whose total intensity is less than said second predetermined intensity is minimized during the absence of said plurality of waves.

24. In combination in a television receiver, means for transmitting a carrier wave having a video signal amplitude modulated thereon, said carrier wave being subject to recurrent shifts in frequency to a predetermined frequency band and being frequency modulated thereover in accordance with an audio signal, an image forming device, means for energizing said image forming device in accordance with the amplitude modulation of said carrier wave, means to synchronize operation of said image forming device with said frequency shifts of said carrier wave, and means to reproduce said audio signal in response to the frequency modulation of said carrier wave.

25. In combination, in a television system having a transmitter of television images, a receiver therefor, a plurality of devices connected with

said receiver to be operated from said transmitter, means in said transmitter for transmitting a train of impulses between transmission of each successive pair of images, each of said trains being effective to cause synchronization of image formation by said receiver with image transmission by said transmitter, means in said receiver to store the impulses of each of said trains, and means responsive to the successive storage of each impulse of each train for initiating the operation of a corresponding one of said devices, said last means being effective to initiate operation of said devices successively as the impulses of each train are stored by said storage means, whereby each of said devices is caused to operate repeatedly in response to corresponding impulses in the successive trains.

26. In combination, in a television system having a transmitter of television images, a receiver therefor, a plurality of devices connected with said receiver to be operated from said transmitter, means in said transmitter for transmitting a train of impulses between transmission of each successive pair of images, each of said trains being effective to cause synchronization of image reproduction by said receiver with image transmission by said transmitter, means in said receiver to store the impulses of each of said trains, means responsive to the successive storage of each impulse of each train for initiating the operation of a corresponding one of said devices, said last means being effective to initiate operation of said devices successively as the impulses of each train are stored by said storage means, and means responsive to termination of each of said trains to restore said storage means to its condition at the beginning of any train, whereby each of said devices is caused to operate repeatedly in response to corresponding impulses in the successive trains.

27. Apparatus for reproducing images and sound accompaniments from transmitted carrier wave energies of a first frequency amplitude-modulated by video signals and interspersed with line synchronizing and frame synchronizing signals of a second and a third frequency respectively, said second frequency being frequency modulated by sound signals, comprising means for receiving the transmitted carriers, means for demodulating the received carriers, means for segregating the video signals from the line synchronizing, frame synchronizing, and audio signals, means for segregating the line synchronizing signals from the frame synchronizing signals, means for limiting the segregated line synchronizing signals, means for frequency-demodulating the limited signals, means for producing sound under the control of the frequency demodulated signals, and means for synthesizing the image field under the control of the segregated video signals and both the line synchronizing and frame synchronizing pulses.

28. Apparatus for reproducing images and sound accompaniments comprising means for producing video signals representative of the image to be reproduced, means for generating carrier oscillations of a predetermined frequency, means for amplitude-modulating the produced carrier oscillations by said video signals, means for generating line synchronizing pulses and frame synchronizing pulses, means for generating signal energy representative of the sound accompanying the video signals, means for interrupting the video signal modulation of the carrier frequency under the control of the line synchronizing pulses, means for shifting the generated carrier frequency to a different value during the intervals of interruption of video signal modulation, means for frequency-modulating the shifted frequency carrier by the sound signal energy, means for periodically shifting the predetermined frequency to a second different value under the control of the frame synchronizing signals, means for transmitting all of said modulated and frequency shifted carrier frequency oscillations, means for receiving the transmitted carriers, means for demodulating the received carriers, means for segregating the video signals from the line synchronizing, frame synchronizing, and audio signals, means for segregating the line synchronizing signals from the frame synchronizing signals, means for limiting the segregated line synchronizing signals, means for frequency-demodulating the limited signals, means for producing sound under the control of the frequency demodulated signals, and means for synthesizing the image field under the control of the segregated video signals and both the line synchronizing and frame synchronizing pulses.

29. Apparatus for transmitting video, line synchronizing, frame synchronizing and audio signals from a single transmitter comprising means for generating carrier oscillations of a predetermined frequency, means for producing video signals, means for producing audio signals, means for amplitude-modulating the carrier oscillation by the produced video signals, means for periodically interrupting said modulation, means for shifting said predetermined frequency to a different value during the intervals of interruption of modulation, means for frequency-modulating the shifted carrier by said audio signals, means for periodically shifting the predetermined carrier frequency to a second different value, said last named periodicity occurring at a lower rate than said first named periodicity, means for modulating distinctively the intensity of both of said shifted carriers, and means for transmitting all of said modulated carriers.

30. Apparatus for transmitting video, line synchronizing, frame synchronizing and audio signals from a single transmitter comprising means for generating carrier oscillations of a predetermined frequency, means for producing video signals, means for producing audio signals, means for amplitude-modulating the carrier oscillation by the produced video signals, means for periodically interrupting said modulation under the control of line synchronizing signals, means for shifting said predetermined frequency to a different value during the intervals of interruption of modulation, means for frequency-modulating the shifted frequency carrier by said audio signals, means for periodically shifting the predetermined carrier frequency to a second different value under the control of the frame synchronizing signals, and means for transmitting all of said modulated carriers.

31. Apparatus for transmitting video, line synchronizing, frame synchronizing and audio signals from a single transmitter comprising means for generating carrier oscillations of a predetermined frequency, means for producing video signals, means for producing audio signals, means for amplitude-modulating the carrier oscillation by the produced video signals, means for periodically interrupting said modulation, means for shifting said predetermined frequency to a different value during the intervals of interruption of modulation, means for frequency-modulating the shifted frequency carrier by said audio signals, means for periodically shifting the predetermined carrier frequency to a second different value under the control of the frame synchronizing signals, and means for transmitting all of said modulated carriers.

32. Apparatus for transmitting video, line synchronizing, frame synchronizing and audio signals from a single transmitter comprising means for generating carrier oscillations of a predetermined frequency, means for producing video signals, means for producing audio signals, means for amplitude-modulating the carrier oscillation by the produced video signals, means for periodically interrupting said modulation, means for shifting said predetermined frequency to a different value during the intervals of interruption of modulation, means for frequency-modulating the shifted frequency carrier by said audio signals, means for periodically shifting the predetermined carrier frequency to a second different value under the control of the frame synchronizing signals, and means for transmitting all of said modulated carriers.

the shifted frequency carrier by said audio signals, means for periodically shifting the predetermined carrier frequency to a second different value, said last-named periodicity occurring at a lower rate than said first named periodicity, and means for transmitting all of said modulated carriers.

32. Apparatus for transmitting signals representative of images and sound accompaniments comprising means for producing video signals representative of the image to be reproduced, means for generating carrier oscillations of a predetermined frequency, means for modulating the produced carrier oscillations by said video signals, means for generating line synchronizing pulses and frame synchronizing pulses, means for generating signal energy representative of the sound accompanying the video signals, means for interrupting the video signal modulation of the carrier frequency under the control of the line synchronizing pulses, means for shifting the generated carrier frequency to a different value during the intervals of interruption of video signal modulation, means for frequency-modulating the shifted frequency carrier by the sound signal energy, means for periodically shifting the predetermined frequency to a second different value

under the control of the frame synchronizing signals, and means for transmitting all of said modulated and frequency shifted carrier frequency oscillations.

- 5 33. A receiver comprising means to receive transmitted wave energy modulated by the signals from a television camera interspersed with frequency modulated sound signals and shifted carrier signals representative of line and frame 10 synchronized pulses, means to detect the received signals, amplitude separator means to segregate the line and frame synchronizing pulses from the camera signals, filter means to separate the line synchronizing pulses from the frame synchronizing pulses, means to control vertical deflection of a cathode ray tube by the separated frame synchronizing pulses, means to control the horizontal deflection of said cathode ray tube by the separated line synchronizing pulses, means 15 for limiting the amplitude of a portion of the separated line synchronizing pulses, means to frequency demodulate the limited line synchronizing pulses, means to reproduce sound by the frequency demodulated pulses and means to control the intensity of the cathode ray and said cathode 20 ray tube by the separated camera signals.
- 25.
